BOBBIN HOISTING MEANS OF STRANDING
AND OTHER MACHINESJohn Hamilton Larmuth, Upper Colwyn Bay,
North WalesApplication May 28, 1942, Serial No. 444,846
In Great Britain July 3, 1941

1 Claim. (Cl. 187—1)

This invention relates to the bobbin hoisting means of stranding and other machines wherein bobbins are hoisted into cradles journaled in a rotary member.

The object of the said invention is to provide a novel construction which is simpler and less costly to produce than previously known constructions and gives a perfectly vertical lift exactly between the sides of the cradle.

The bobbin hoisting means of a stranding or other machine in accordance with my invention comprises bobbin platforms situated vertically beneath the cradles and slideable on fixed vertical guide posts and means for lifting the platforms along a vertical path determined by the vertical guide posts.

The means for lifting the platforms may comprise chains or cables which pass over chain wheels or pulleys provided on snatch blocks connected to the platforms and can be wound over chain wheels or onto and off a winding barrel to lift and lower the platforms so as to hoist the drums into or lower them out of the cradles from below.

A single sprocket wheel shaft or a single winding barrel may be provided to operate each of two platforms separately.

A single pair of chains may be provided to operate each of two platforms separately, each chain being anchored at one end and the said chains passing over idle wheels situated at a similar elevation to the anchored ends of the chains, whilst the sprocket wheel shaft is mounted at a lower elevation and the chains engage sprocket wheels thereon.

I attain this object by the means illustrated in the accompanying drawings, wherein—

Figure 1 is a fragmentary side view, partly in section, of a bobbin hoisting means of a stranding or the like machine.

Figure 2 is a front view thereof, partly in section.

Figure 3 is a detached diagrammatic side view drawn to a smaller scale and illustrating a disposition of parts.

Figure 4 is a similar view to Figure 3, but with parts in a different operative position.

Figure 5 is a plan view of the said bobbin hoisting means.

Referring to the drawings, in the construction shown therein, as applied by way of example to the hoisting of bobbins into two adjacent cradles 37 and 38 journaled in the rotary member 1 of a stranding machine, I provide beneath each cradle a platform 2 on which the bobbin 36 can

stand with its central hole horizontal. The platform 2 is mounted on and projects above a channel iron 3 which is connected at each end by a pivotal pin 4 to a snatch block 5 each of which has a pair of lugs 6, one lug 6 of each pair being situated vertically above the other. Each lug 6 has in it a vertical hole which may be of elongated form. The holes of each pair of lugs 6 is engaged by a stationary vertical guide post 7, there being therefore two guide posts 7 for each platform 2. On each snatch block 5 there is a rotatably mounted snatch sprocket wheel 8 which lies at the bottom of a depending loop in a pivotal link chain indicated in Figure 1 by the dot-and-dash line 9 and meshing with the sprocket wheel 8.

One end of the chain 9 is situated at the end of one side of the loop and is anchored at 10 to a member 11 connected by bolts to each side member 12 of the frame of the stranding machine. The member 11 carries an idle sprocket 13 over which the upper end of the other side of the chain loop passes. Each member 11 has a lug 14 by which the upper end of one post 7 is secured, the lower end of the two posts being secured to a stationary plate 15.

From the idle sprocket wheel 13 the chain 9 extends horizontally to an idle sprocket wheel 16 carried by a member 17 secured by screws to the frame member 12. The chain 9 extends over the idle sprocket wheel 16 and then downwards over the under side of a hoisting sprocket wheel 18 with which it meshes. From thence the chain 9 extends upwards, then over an idle sprocket wheel 19, then horizontally, then over an idle sprocket wheel 39, Figure 3, similar to the wheel 13, then downwards to form a loop engaged by the snatch sprocket wheel 40, which is similar to the sprocket wheel 8, and having the top of one of its sides anchored to a third member also indicated by the reference numeral 11 in Figure 5 and similar but reversed to the member 11 which is screwed to the frame member 12 at the same elevation as the member 11 and carries the idle sprocket wheel 39. The idle sprocket wheel 19 is carried by the member 17. The total length of the chain 9 is sufficient to permit both of the sprocket wheels 8 and 40 to rest in their lowermost positions simultaneously, as indicated in Figure 3.

The two hoisting sprocket wheels 18 are provided on a horizontal shaft 20 journaled in the two members 17 and having a hand wheel 41 or the like whereby it can be rotated and a catch or other releasable locking device whereby it can be held in various positions against rotation. A locking device is shown and consists of a brake

drum 21 mounted on the shaft 20 and cooperating with a band brake 22 one end of which is connected at 23 to one of the members 17 and the other end of which is pivotally connected at 24 to a hand lever 25 rotatably connected at 26 to the said member 17 and adapted to be secured in various positions by means of a pawl 27 mounted on the lever 25 and cooperating with a ratchet rack 28 secured to the frame member 12.

The surface of each platform has two hollows or depressions 29 engageable by the flanges of the bobbin 3 to prevent accidental rolling off of the bobbin. The said surface also has a sunk surface 30 to reduce the possibility of the bobbin riding on the stranding material with which it is filled before insertion in the cradle.

The platform 2 fits between rail sections 31 along which the bobbin can be rolled. The rail sections are supported by brackets 32 secured to the plate 15 and having lugs 33 which by engagement with corresponding recesses in the underside of the platform 2, temporarily fixes the position of the platform and thereby ensures correct registration of the platform 2 and its flanges 34 with the rail sections 31 and their flanges, so that the bobbin can be rolled without hindrance from the rail sections onto or over the platform.

In operation, when no bobbin requires to be removed and replaced, all the sprocket wheels 8 and 40 lie in their lowermost positions, see Figure 3, and therefore the platform 2 by which the sprocket wheels 8 are carried and the second platform 2 by which the sprocket wheels 40 are carried are at rest in their lowermost position. When the bobbin in one cradle has become empty and requires to be removed and replaced by a full bobbin, the hoisting handle is rotated in the requisite direction so as to cause the two chains 9 to be moved by the hoisting sprocket wheels 18 and the loops thereof containing the snatch sprocket wheels 8 of the two snatch blocks 5 of the platform 2 under the said cradle to be shortened. The shortening of the loops acts to lift the two snatch blocks 5 and therefore the channel iron 3 and the platform 2. The direction of the upward path of the raised platform 2 is governed by the sliding engagement of the lugs 6 of the snatch blocks 5 with the two vertical posts 7, only a limited amount of lateral movement of the platform 2 being permitted by the elongation of the holes in the said lugs 6, if the said holes are elongated. Therefore the raised platform 2 is guided along a path which automatically and positively ensures its upward passage vertically into a position where its hollows or depressions 29 engage the rims of the empty bobbin and it supports the said bobbin. After withdrawal of the spindle which supports the bobbin in the cradle, the hoisting sprocket wheels 18 are allowed to rotate in the reverse direction by releasing the brake 22 sufficiently and therefore the said loops to lengthen again and con-

sequently the platform 2 to descend and thereby lower the empty bobbin until it can be rolled off the platform 2 onto a rail section 31. The full bobbin is then rolled on to the platform 2 and the hoisting operation repeated. Figure 4 indicates the position of the chain when for example the sprocket wheels 8 and therefore the platform 2 which carries them has been raised to the uppermost position. Due to guidance of the platform by the vertical posts 7, the full bobbin is automatically and positively constrained to a vertical path which brings it into the cradle exactly between and clear of the sides of the cradle, without adjustment or guidance by hand. The supporting spindle is then slipped into position, and the platform 2 allowed to descend to its initial position. By rotating the hoisting shaft 20 in the requisite direction the second platform 2 can be raised and lowered to remove and replace an empty bobbin by a full bobbin in the second cradle. The slack of the chains 9 which occurs in the hoisting of either platform can be received by a shelf 35 provided on each snatch block 5 below its upper surface. Figure 2 shows in dot-and-dash lines, the position of the parts when one of the platforms has been raised a portion of its upward traverse.

The depressions or hollows 29 are not sufficiently deep to prevent a bobbin from being forcibly rolled over one platform onto a rail section 31 in its approach to another platform.

In lieu of chains, cables may be employed in which case the snatch and idle wheels are in the form of grooved pulleys and there is a pair of cables for each platform, two adjacent ends of each pair being anchored as hereinbefore described, whilst the other two adjacent ends are connected to a barrel which is substituted for the hoisting sprocket wheels. The one pair of cables runs on to the upper side of the barrel whilst the other pair runs on to the under side of the barrel. Therefore one pair winds on to the barrel and the other pair winds off the barrel when the hoisting shaft is rotated.

I claim:

A bobbin hoisting means of a stranding machine wherein a bobbin is hoisted into a cradle, comprising a stationary base member at the base of the machine, brackets fixed to the machine at the sides thereof, guide rods fixed at their upper ends to the brackets and at their lower ends to the said stationary base member, snatch blocks slidably mounted on the guide rods, a cross member connected at each end to one of the snatch blocks, a bobbin platform mounted on the cross member and secured to the cross member vertically beneath the cradle, and means for lifting the snatch blocks and therefore the cross member and bobbin platform and thereby hoisting a bobbin into the said cradle.

JOHN HAMILTON LARMUTH.
